Primary Examiner — Ricky Pham(74) *Attorney, Agent, or Firm* — FisherBroyles, LLP; Anthony J. DoVale(57) **CLAIM**

The ornamental design for the stadium seat, as shown and described.

DESCRIPTION

FIG. 1 is a front left perspective view of one aspect of a stadium seat;

FIG. 2 is a front right perspective view of the stadium seat of FIG. 1;

FIG. 3 is a front elevational view of the stadium seat of FIG. 1;

FIG. 4 is a left side elevational view of the stadium seat of FIG. 1;

FIG. 5 is a rear elevational view of the stadium seat of FIG. 1;

FIG. 6 is a top plan view of the stadium seat of FIG. 1;

FIG. 7 is a right side elevational view of the stadium seat of FIG. 1; and,

FIG. 8 is bottom elevational view of the stadium seat of FIG. 1.

1 Claim, 8 Drawing Sheets---
